UNITED STATES PATENT OFFICE.

STEPHEN MORRIS, OF NEWCOMER, PENNSYLVANIA.

INCLINE SAFETY-CATCH.

1,109,693.

Specification of Letters Patent.

Patented Sept. 8, 1914.

Application filed May 2, 1914. Serial No. 835,960.

To all whom it may concern:

Be it known that I, STEPHEN MORRIS, a citizen of Austria-Hungary, residing at Newcomer, in the county of Fayette and State of Pennsylvania, have invented certain new and useful Improvements in Incline Safety-Catches, of which the following is a specification, reference being had to the accompanying drawings.

10 This invention has for its primary object a simple, durable and efficient construction of mechanism for preventing the cars or trips from running backward down an inclined plane in the event of an accident to the hoisting power or its connections to the car, or in the event of the power being turned off unexpectedly and before the brakes can be applied, or from any other defect in the couplings or other connections, or the hoisting power itself.

With this object in view, the invention consists in certain constructions, arrangements and combinations of the parts that I shall hereinafter fully describe and claim.

25 For a full understanding of the invention, reference is to be had to the following description and accompanying drawing, in which—

Figure 1 is a side elevation of a portion of an inclined track embodying the improvements of my invention. Fig. 2 is a plan view thereof. Fig. 3 is a transverse sectional view on the line 3—3 of Fig. 2. Fig. 4 is a section on the line 4—4 of Fig. 2. Fig. 5 is a detail sectional view through one of the shafts showing the crank arm mounted thereon, and Fig. 6 is a detail section on the line 6—6 of Fig. 2.

Corresponding and like parts are referred to in the following description and designated in all of the views of the accompanying drawing by like reference characters.

Referring to the drawing, the numeral 1 designates the track rails of an inclined road bed, and 2 designates the cross ties thereof. In carrying out my invention, I provide a number of transversely extending shafts 3, the number varying according to the length of the incline and its pitch and the shafts being located any predetermined distances apart, according to the particular requirements of the case. In the present instance, the shafts 3 are journaled near their ends in pairs of brackets 4, which are bolted or otherwise secured upon opposite sides of the track rails 1 and which depend there-

from as clearly illustrated in the drawing. One end of each shaft is provided with a counter-weight arm 5, and between the track rails 1, each shaft carries any desired number of trip arms 6, there being two arms for each shaft in the present instance, although it is to be understood that the invention is not limited to that or any other number of said arms. The arms project perpendicularly from the shafts 3 and in one position are held by gravity, through the instrumentality of the counter-weight arms 5 in a position perpendicular to the track rails and against abutment blocks 7 which are carried by and project upwardly from the adjoining cross ties 2.

From as much of the description as has preceded, in connection with the accompanying drawing, it will be understood that as a car moves upwardly on the inclined track rails 1, its bottom will strike the trip arms 6 and pass over the pairs of arms in succession and that immediately after the car has passed one set of arms, such arms will move 80 backwardly again into operative position above the track rails, whereby should anything happen to the equipment and should the car start to move backward down the incline, its movement will be effectively obstructed and prevented by the engagement with the upwardly projecting trip arms and accidents being thereby prevented.

In order to hold the arms 6 in an inoperative position down below the track rails, 90 or at least sufficiently low to allow the car to move downwardly when required, the transverse shafts 3 are provided at their ends opposite the counter-weight arms 5 with crank arms 8 which preferably project 95 upwardly, as shown, said arms being operatively connected together to move simultaneously by being pivotally secured between the link bars 9. The link bars 9 pass at one end between two laterally spaced quadrant 100 bars 10 and preferably underneath and in engagement with, a roller 11, and said ends of the link bars are pivotally connected to a lever 12. Thus, it will be understood that when the lever 12 is swung in one direction 105 by the operator or attendant, at the side of the track, the trip arms 6 will be moved to a depressed and inoperative position so as to permit the cars to travel down the incline. Preferably, in order to hold the parts in inoperative position, the quadrant bars 10 are 110 apertured, and a rod 12^a passed through the

apertures across from one quadrant bar to the other, and either through a registering aperture in the lever 12, or, if desired, the lever may rest with its side edge against the rod 12^a.

In the practical use of this safety mechanism, as the cars ascend the incline, they will engage the pairs of trip arms 6 in succession and should the power give out or should anything else happen to it or to the connections between it and the cars, manifestly, the car will be prevented from moving down the incline by engagement with the upwardly projecting trip arms. When it is desired to have the car pass down the incline, it is only necessary for the attendant to manipulate the lever 12 and to secure it in position to hold the trip arms inoperative.

It is to be particularly noted that the shaft 3 is formed with a segmental transversely extending recess 3^a, and that the boss or hub of the crank arm 8 is formed with a lug 8^a working in said recess. Consequently, each shaft 3, with its trip arms 6, is permitted to have a free movement and of limited length in one direction without disturbing the crank arms 8 and their connections, whereby each pair of trip arms may operate independently of all the others when the car is ascending the incline, while on the other hand, when the actuating lever 12 is manipulated, manifestly the engagement of the lugs 8^a with the ends of the recesses 3^a, will cause the shafts 3 to turn and positively swing the trip arms to their inoperative positions.

While the accompanying drawings illustrate what I believe to be the preferred embodiment of my invention, it is to be understood that the invention is not limited thereto, but that various changes may be made in the construction, arrangements and proportions of the parts without departing from the scope of the invention as defined in the appended claims.

What is claimed, is:

1. The combination with an inclined track including cross ties and track rails, of pairs of brackets secured on opposite sides of the track rails and depending therefrom, shafts journaled near their ends in said brackets and extending transversely of the track rails underneath the latter, trip arms secured to said shafts between the track rails and pro-

jecting perpendicularly from the shafts, the cross ties being provided with abutment blocks against which the trip arms are adapted to rest, counter-weight arms secured to the shafts at one end thereof and at one side of the track, crank arms secured to the other ends of the shafts and on the other side of the track, link bars pivotally connected to the crank arms, quadrant bars located on the said side of the track as the link bars, a lever mounted to move between said quadrant bars and pivotally connected intermediate of its ends to one end of the link bars and a pin adapted to extend across from one quadrant bar to the other to hold the lever and the other parts in an inoperative position.

2. The combination with an inclined track, including track rails, of shafts extending transversely underneath the track rails, means for supporting said shafts, trip arms secured on said shafts, intermediate of the rails, counter-weight arms connected to the shaft at one end of the latter and tending to move the shafts in one direction, means for stopping this movement of the shafts with the trip arms projected above the track rails, cranks mounted on the other ends of said shafts, means for moving said cranks, and a lost motion connection between said cranks and shafts, as and for the purpose set forth.

3. The combination with an inclined track, including track rails, of shafts extending transversely underneath the track rails, means for supporting said shafts, trip arms secured on said shafts, intermediate of the rails, counter-weight arms connected to the shaft at one end of the latter and tending to move the shafts in one direction, means for stopping this movement of the shafts with the trip arms projected above the track rails, cranks mounted on the other ends of said shafts, means for moving said cranks, the shafts being formed with transverse recesses, and the crank arms being provided with lugs movable in said recesses, as and for the purpose set forth.

In testimony whereof I hereunto affix my signature in the presence of two witnesses.

STEPHEN MORRIS.
